UNITED STATES PATENT OFFICE.

JOSEPH J. MCNEILL, OF CLEVELAND, OHIO.

DEVICE FOR MANIPULATING INGOTS, BILLETS, &c.

SPECIFICATION forming part of Letters Patent No. 639,270, dated December 19, 1899.

Application filed February 10, 1899. Serial No. 705,188. (No model.)

To all whom it may concern:

Be it known that I, JOSEPH J. MCNEILL, a resident of Cleveland, county of Cuyahoga, and State of Ohio, have invented certain new and useful Improvements in Devices for Manipulating Ingots, Billets, and other Metallic Forms; and I do hereby declare the following to be a full, clear, and exact description of the invention, such as will enable others skilled in the art to which it pertains to make and use the same.

My invention relates to improvements in devices for holding ingots, fagots, billets, and the like during the process of forging into a predetermined shape or during other operations upon the same.

The object of this invention is to render the manipulation of work of the character indicated more convenient and easier and lessen, and consequently reduce, the cost of the labor and time required to manipulate and perform the operations upon the work.

With this object in view the invention consists in certain features of construction and combinations of parts hereinafter described, and pointed out in the claims.

In the accompanying drawings, Figure I is a side elevation of a device embodying my invention. Fig. II is a side elevation in central longitudinal section. Fig. III is a transverse section on line III III, Fig. I, looking in the direction of the work-grasping end of the device. Fig. IV is a forward end elevation.

In Figs. I and II the two work-holding jaws of the device are shown closed together. In Fig. IV the said jaws are shown separated the maximum distance. The work *w* is shown in position in Figs. I and II.

My improved device comprises two jaws *a* and *b*, that correspond generally in shape or contour and are shaped as required to embrace or engage opposite sides, respectively, of the work. The jaws are preferably shaped internally as required to render them capable of grasping or receiving work that is quadrangular in cross-section, and consequently in the case illustrated each jaw is provided with a chamber *c*, that is V-shaped in end elevation, open at the jaw's inner side, and registers with the chamber *c*, formed within the companion jaw. The jaws are secured in their operative position in any ap-

proved manner, and preferably by two clamps arranged at opposite ends, respectively, of the assembled work-holding jaws. Each clamp 55 comprises, preferably, two jaws *d* and *e*, arranged the one *d* at the outer side of one of the jaws and the other, *e*, at the outer side of the companion jaw, and both of the clamping-jaws of each clamp are secured in their 60 operative position by two bolts *g* and nuts *g'*, mounted upon the correspondingly-threaded shanks of the bolts. The bolts *g* extend through the clamping-jaws at opposite sides, respectively, of the clamp and have their 65 heads bearing against the outer side of one of the clamping-jaws, and the bolt-engaging nuts *g'* are arranged to bear against the outer side of the companion clamping-jaw. One of the work-holding jaws is adjustable toward 70 and from the companion jaw, and the said adjustable jaw is shiftable endwise and removable from the companion jaw. The work-holding jaws correspond in length, and the arrangement of parts is such, preferably, that 75 in the assembled and operative position of the said jaws the adjustable jaw has its rear end abutting the stop *a'* and has its forward or outer end flush with the corresponding end of the companion jaw.

The tool-shank is not only for the purpose of accommodating the provision of handles *h*, from which the tool is manipulated and which are preferably adjustable endwise of the shank, as shown; but the shank is primarily 85 for the purpose of forming a counterbalance for the work, and thereby facilitating the manipulation of the work.

The tool is supported, preferably, from a chain *k*, depending from a crane overhead, 90 which chain may be applied between the two clamps upon the jaws, as shown, or at or near the inner end of the shank. The chain, it will be observed, forms a fulcrum for the tool, and upon this fulcrum the tool can be turned and 95 tilted or swung in any direction, and it is obvious that the chain or fulcrum is adjustable, therefore, longitudinally of the tool, as required, to cause the work preparatory to the tool's operation to be properly counterbalanced. In the case illustrated jaw *b* is the adjustable jaw, and its adjustability accommodates the use of the tool for different sizes of work. The lateral adjustability of jaw *b*

toward and from its companion jaw is attained, preferably, as follows: The said adjustable jaw at its rear or inner end is provided with a journal or trunnion b' . The said trunnion 5 has its lower or inner half extending rearwardly from the inner end wall of the chamber of the adjustable work-holding jaw and projects inwardly from the inner or open side of the said jaw into a corresponding depression or recess a' , formed in the inner end wall a^2 of the companion jaw. The entire trunnion of the adjustable jaw extends rearwardly from the said jaw a suitable distance, and the said rearwardly-extending cylindrical portion of 10 the trunnion engages a bore a^4 , formed in and centrally of the inner and diametrically-enlarged end of the shank a^3 of the tool. The said bore a^4 is elongated in the direction required to accommodate the adjustability of 15 the trunnion-bearing jaw toward and from the companion jaw, and the recess a' forms a forward extension of the said bore.

It will be observed that the inner and enlarged end of the tool's shank overlaps, as at 20 a^5 , the rear end of the adjustable jaw and has the arrangement required to form an abutment or stop for the said adjustable jaw and prevent rearward displacement of the said 25 jaw.

30 My device is especially well adapted for holding the work during the forging of iron shafting and other shapes from loosely-assembled iron bars or billets and for holding a steel ingot during any operation performed upon 35 the ingot and is capable of holding work of any cross-sectional form—square, round, or oval—and the construction illustrated, wherein the adjustable work-holding jaw is trunnioned within the shank, accommodates a 40 limited tilting of the said jaw laterally, and thereby facilitates the said jaw in conforming to the work, and thereby more effectually rendering the said jaw capable of grasping work of any cross-sectional form. It will be 45 observed also that the adjustable jaw, when the clamps are loosened and no work is being held, is shiftable endwise of and separable

from the relatively stationary jaw to accommodate access to the bore a^4 for cleaning the latter.

What I claim is—

1. A tool of the character indicated, comprising two work-holding jaws arranged opposite each other, one of the jaws adjustable toward and from the companion jaw and provided, at its rear end and inner side, with a trunnion or member projecting rearwardly and arranged longitudinally of the jaw, a rearwardly-extending counterbalance-forming member formed upon the rear end of the non-adjustable jaw and having a bore engaged by the aforesaid rearwardly-projecting member of the adjustable jaw, which bore is elongated in the direction required to accommodate the adjustability of the last-mentioned jaw, and means for securing the jaws in their operative position.

2. A tool of the character indicated, comprising two work-holding jaws arranged opposite to each other, and having one of said jaws adjustable toward and from the companion jaw, means for securing the jaws in their operative position, a journal or trunnion formed upon the adjustable jaw at the rear end and inner side of the said jaw, which trunnion extends rearwardly of the jaw and has its lower half or portion elongated forwardly over the inner end wall of the adjustable jaw, a handle-bearing and work-counterbalancing shank formed upon the rear end of the non-adjustable jaw and provided, in its inner end, with a bore arranged to receive the outer or free end of the aforesaid trunnion and elongated, as required, to accommodate the adjustability of the adjustable jaw, which bore is extended forwardly into the inner end wall of the non-adjustable jaw.

Signed by me at Cleveland, Ohio, this 1st day of February, 1899.

JOSEPH J. MCNEILL.
